UNITED STATES PATENT OFFICE

IRVING WARNER, OF NEW CASTLE, DELAWARE, ASSIGNOR TO AMERICAN MANGANESE STEEL COMPANY, OF CHICAGO HEIGHTS, ILLINOIS, A CORPORATION OF MAINE

ONE-PIECE BUCKET AND ATTACHING LINK

Application filed February 18, 1929. Serial No. 340,960.

This invention relates to improvements in link bucket construction and generally to an improved means for attaching the links to the bucket. My improved link bucket may 5 be used for dredging or other purposes in which an endless chain is formed having a plurality of buckets secured thereto, the chain passing around sprocket wheels at upper and lower ends whereby the bucket automatically 10 fills with material in passing around the lower end and dumps the material at the top.

It is the purpose of my invention to provide one piece buckets having links secured thereto in which the links are provided with 15 integral attaching bases.

It is further a purpose of my invention to so secure the link bases to the buckets that the whole assembly is substantially rigid and as strong as a one piece casting.

20 In particular it is an object of my invention to provide integral lugs on the ends of the bucket and to provide link bases which are held between the lugs and bolted to the bucket.

25 It is further an object of my invention to provide recesses between the link bases and the bucket wall thus allowing the bolts to be more tightly secured by slightly springing the bases and to form a secure connection by 30 filling the recesses with Babbitt metal after the bolts have been drawn tight.

It is another object of my invention to allow clearance spaces between the integral lugs on the bucket and the link bases in which 35 wedging strips may be placed which are subsequently welded both to the bucket and the link bases in order to form a rigid and tight connection.

Other objects and advantages of my improved construction will be more clearly apparent as the description proceeds in connection with the attached drawings in which—

40 Figure 1 is an end elevation of a bucket showing the means of attaching one of the links.

Figure 2 is a rear elevation from the right end side of Figure 1.

45 Figure 3 is a detail section on line 3—3 of Figure 1.

Figure 4 is a detail view in section on line 4—4 of Figure 1.

55 My invention is illustrated in the accompanying drawings in connection with an ordinary form of dredge or excavating bucket adapted to be connected in an endless chain. I show a bucket 1 formed from a single one piece casting usually comprising manganese steel. The bucket is designed with ends 2 and 3, a forward lip 4 to which an additional 60 separate digging lip may be attached in the usual manner and a rearward side 5.

A pair of links, denoted generally as 6 and 7, are attached to either end 2 and 3 on the bucket. It will be apparent that it might 65 be possible to integrally cast the links with the bucket but in forming the bucket from manganese steel difficulties arise in the casting operation which render such a construction impracticable.

70 It is, therefore, the problem of this invention to provide a means by which the links may be secured to the bucket in such a manner that a connection having the greatest strength and rigidity may be secured. In 75 buckets of this type, which are subjected in use to heavy stresses and loads, the connection must be one which will not work loose. Further, the spaces between the links 6 and 7 must be substantially accurate in order that 80 the sprocket wheels will correctly engage with the links. I therefore provide a link, which will be described in connection with link 6 only since the construction on the other side will be similar, in which there is an outside link plate 8 connected to an attaching base 9 by horizontal sprocket engaging members 10 and 11 thus leaving a recess 12 for the reception of a sprocket tooth. The base 9 seats against the end 2 of the bucket along 85 its outside edges only shown at 13, 14, 15 and 16 in the detail sectional views Figures 3 and 4. These edges 13, 14, 15 and 16 must be

90 ground smooth for correct seating engagement and it is necessary to make the thickness 95 of the attachment base 9 such that the space between the links 6 and 7 corresponds to the space between the sprocket wheels. This may be done by grinding the seating edges 13, 14, 15 and 16 or by inserting shims be- 100

tween the bases and the bucket. A central rectangular opening 17 is provided in the base 9 extending parallel to the link 6. A recess 18 extends from the seating edges 13, 14, 15 and 16 to the central opening 17. A plurality of bolt receiving openings 19 are provided extending through the base 9 and having recesses 20 in the outer side in which the nuts 21 are received. As stated, the base 9 is secured directly against the end 2 of the bucket which is provided with upper and lower parallel lugs 22-23 spaced apart a distance somewhat wider than the length of the base 9 thus leaving spaces between the lugs 22-23 at the ends of the base 9 for wedging members 24 and 25. The inner ends of the lugs 22-23 are braced by strengthening webs 26 and 27. Bolt receiving openings 28 corresponding to the openings 19 are provided in the bucket wall 2. The bucket wall is further designed with an integral projecting lug 29 which is somewhat smaller than the central opening 17 formed in the base 9. The lug 29 is rectangular in shape and extends normal to the parallel lugs 22-23. The link is attached by placing the base 9 in position, inserting the wedges 24-25 in the spaces provided and inserting the bolts 30 from the inner side of the bucket and connecting the nuts 21. The nuts 21 may be drawn tight and it is apparent that the recess 18 between the base 9 and the bucket wall 2 allows the bolts to draw the base 9 into a tight engagement with the bucket by slightly springing the wall of the attaching base. After the bolts and nuts have been secured the recess 18 beneath the base 9 and the recess 31 around the central lug 29 may be filled with Babbitt metal 32 in order to securely anchor the parts. In addition, the recessed openings 20 surrounding the nuts 21 may be filled with Babbitt metal in order to securely anchor the nuts in place. Finally, in order to securely hold the wedges 24-25 in place the parts are welded. Thus, in Figure 3 welding metal 33 is shown extending from lug 26 across wedge 24 and joining to the end of the base 9; similarly, the lower wedge 25 is secured by the weld 34.

It will be apparent that I have provided a very rigid construction which is substantially as strong as that which would be secured by a one piece casting. The lugs and wedges prevent the application of shearing stresses on the bolts while the bolts and the anchoring Babbitt metal prevent any loosening of the parts. It is obvious that my invention does not depend upon the particular position in which the base 9 is secured and the bases could be as well attached to the back 5 of the bucket.

Further, it is apparent that the arrangement and design of the lugs and openings may be greatly modified without departing from the spirit of my invention as expressed

in the appended claims and further it may not be necessary to use a full combination of the bolted, babbitted and welded construction. The construction has been described in connection with a bucket using an endless chain but a similar form of construction could be used with other forms of buckets.

I claim:

1. In a link bucket construction, a bucket, a pair of links, attachment bases formed integral with said links, a pair of lugs integrally formed with said bucket spaced apart a distance greater than the length of said base and means for securing one of said bases to said bucket comprising wedges inserted between said lugs and said base and additional securing means comprising a weld joining said wedges to said lugs and said base.

2. In a link bucket construction, a bucket, a pair of links, attachment bases formed integral with said links, each of said bases having a recess in its attaching side whereby said base seats against said bucket along its outside edges and means filling said recess comprising Babbitt metal.

3. In a link bucket construction, a link adapted to be secured to said bucket, a lug integrally formed with said bucket projecting through an opening in said link, said opening being slightly larger than said lug, said link seating against said bucket along its outside edges and having a recessed portion extending from the seating edges to the lug receiving opening, means filling said recess and the space between said lug and the sides of said opening adapted to secure said link to said bucket.

4. In a link bucket construction, a link adapted to be secured to said bucket, a lug integrally formed with said bucket projecting through an opening in said link, said opening being slightly larger than said lug, said link seating against said bucket along its outside edges and having a recessed portion extending from the seating edges to the lug receiving opening, means filling said recess and the space between said lug and the sides of said opening adapted to secure said link to said bucket, and fastening means extending through said link and said bucket.

5. In a link bucket construction, a link adapted to be secured to said bucket, a lug integrally formed with said bucket projecting through an opening in said link, said opening being slightly larger than said lug, said link seating against said bucket along its outside edges and having a recessed portion extending from the seating edges to the lug receiving opening, means filling said recess and the space between said lug and the sides of said opening adapted to secure said link to said bucket, integral lugs on said bucket adjacent the ends of said link and wedges filling the spaces between said lugs and said link.

6. In a link bucket construction, a link adapted to be secured to said bucket, a lug integrally formed with said bucket projecting through an opening in said link, said opening being slightly larger than said lug, said link seating against said bucket along its outside edges and having a recessed portion extending from the seating edges to the lug receiving opening, means filling said recess and the space between said lug and the sides of said opening adapted to secure said link to said bucket, integral lugs on said bucket adjacent the ends of said link, wedges filling the spaces between said lugs and said link, and fastening means extending through said link and said bucket.

7. An attachment between a body and a plate comprising a lug integrally formed with said body projecting through an enlarged opening in said plate, said plate seating against said body along its outside edges and having a recessed portion extending from its seating edges to the enlarged opening, means filling said recess and the space between said lugs and said plate in order to form a tight connection.

8. An attachment between a body and a plate comprising a lug integrally formed with said body projecting through an enlarged opening in said plate, said plate seating against said body along its outside edges and having a recessed portion extending from its seating edges to the enlarged opening, means filling said recess and the space between said lug and said plate in order to form a tight connection, and fastening means extending through said plate and said body.

9. An attachment between a body and a plate comprising a lug integrally formed with said body projecting through an enlarged opening in said plate, said plate seating against said body along its outside edges and having a recessed portion extending from its seating edges to the enlarged opening, means filling said recess and the space between said lug and said plate in order to form a tight connection, integral lugs formed with said body adjacent the ends of said plate and wedges filling the spaces between said lugs and said plate.

10. An attachment between a body and a plate comprising a lug integrally formed with said body projecting through an enlarged opening in said plate, said plate seating against said body along its outside edges and having a recessed portion extending from its seating edges to the enlarged opening, means filling said recess and the space between said lug and said plate in order to form a tight connection, integral lugs formed with said body adjacent the ends of said plate, wedges filling the spaces between said lugs and said plate, and fastening means extending through said plate and said body.

11. In a link bucket construction, a bucket,

a link, an attaching base for securing said link to said bucket, said base being recessed on its attaching side whereby it seats along its outer edges and securing means extending through the recessed portion of said base and said bucket for tightly clamping the base and link to the bucket.

12. In a link bucket construction, a bucket, a pair of links adapted to be attached to said bucket, attachment bases formed integral with each link, each of said bases being recessed on its attaching side whereby it seats along substantially narrow edges and securing means extending through the recessed portion of said base and said bucket for tightly clamping the links to said bucket.

Signed at New Castle, Delaware, this 25th day of January, 1929.

IRVING WARNER.
